[57] CLAIM

The ornamental design for an album, as shown and described.

DESCRIPTION

FIG. 1 is a top plan view of an album showing my new design;

FIG. 2 is a left side elevational view;

FIG. 3 is a front elevational view;

FIG. 4 is a right side elevational view;

FIG. 5 is a bottom plan view;

FIG. 6 is a rear elevational view; and,

FIG. 7 is a left side perspective view.

The face on the pocket drawn in phantom lines is for illustrative purposes and does not constitute part of the claimed design.

FIG. 1

FIG. 2

FIG. 3

FIG. 4

FIG. 5

FIG. 6

FIG. 7
